COLLAPSIBLE CORE

Emery W. Morse, Sunnyvale, Calif.

Application June 17, 1947, Serial No. 755,074

4 Claims. (Cl. 25—128)

1

The present invention relates to improvements in a collapsible core, and has particular reference to a core adapted to be employed in constructing hollow concrete walls. It consists of the combinations, constructions and arrangement of parts hereinafter described and claimed.

An object of my invention is to provide an improved collapsible core to be used in forming air columns in concrete walls during pouring of the concrete. It is well known that such air columns prevent the walls from becoming damp, and further provide good insulation.

The core is in the nature of an expandable and contractible form. In constructing a hollow concrete wall, the core is expanded and supported between the usual form boards provided for the wall. After a course of concrete has been poured and allowed to set, the core is contracted so that it may be raised to a higher level between the form boards for pouring another course of concrete. Then the core is expanded again with its lower end anchored in the air column provided by the previous pouring. These steps are repeated until the wall has reached the desired height.

More specifically described, I provide opposing core plates that are arranged to define a conduit-like form. A central post is disposed lengthwise of the form along the longitudinal axis thereof. This post is operable from a position above the form. When the central post is moved endwise in one direction, the core-like form is expanded outwardly while maintaining the plates in contact with one another. Upon moving the central post in the opposite direction, the form is contracted, thus freeing the plates from the concrete walls of the air column.

Another object of my invention is to provide a collapsible core of sturdy construction, that is durable and efficient for the purpose intended, and which is easy to operate.

Other objects and advantages will appear as the specification continues. The novel features will be set forth in the claims hereunto appended.

For a better understanding of my invention, reference should be had to the accompanying drawings, forming part of this application, in which:

Figure 1 is a plan view of a concrete wall constructed with my collapsible core when used to provide air columns in the wall during pouring thereof;

Figure 2 is an isometric view of the collapsible core in expanded position;

Figure 3 is an isometric illustration of the collapsible core with the core plates and top cover

2

removed so as to disclose the interior arrangement, the upper part of the central post being cut away;

Figures 4 and 5 are isometric views of an angle bracket and a cam track, respectively, that I employ;

Figure 6 is a plan view of my collapsible core;

Figures 7 and 8 are vertical sectional views taken along the lines VII—VII and VIII—VIII, respectively, of Figure 6;

Figure 9 is a horizontal transverse sectional view taken along the line IX—IX of Figure 8, the form being expanded; and

Figure 10 is a view similar to Figure 9, but illustrating the form contracted.

While I have shown only the preferred form of my invention, it should be understood that various changes, or modifications, may be made within the scope of the annexed claims without departing from the spirit thereof.

Referring to the drawings in detail, I provide a collapsible core indicated generally at A. In constructing a concrete wall B (see Figure 1), the usual form boards 1 are arranged in spaced-apart

relation with one another. These boards are supported by retainer posts 2 disposed at intervals on the outer faces of the form boards. Spreaders 3 are used to hold the form boards from moving inwardly. Vertical air columns 4 are provided in the concrete wall during pouring thereof by employing my collapsible core. The sequence of the steps will be described more fully after the details of the core are set forth.

The collapsible core A includes a pair of opposing core plates 5 and a second pair of opposing core plates 6. These two pairs are arranged at right angles to one another and provide a form substantially rectangular in cross section (see Figures 9 and 10). The plates 5 and 6 are fashioned with 45° marginal flanges 5a and 6a, respectively, which extend lengthwise along opposing side edges thereof. The flanges 5a and 6a are arranged in overlapping and sliding relation with each other to define a conduit-like form.

As the core is expanded or contracted in the manner hereinafter described, the flanges 5a and 6a, maintain contact, thus preventing freshly poured concrete from entering the hollow interior 1 of the core.

Referring now to Figures 3 and 7 to 10, inclusive, I have shown a pair of side posts 8 having the core plates 5 secured thereto by screws 8a. Likewise, the core plates 6 are secured to a pair of side posts 9 by screws 9a. The side posts 8 and 9 reinforce the plates 5 and 6, respectively, and

extend substantially throughout the entire lengths thereof (see Figures 7 and 8). A central post 10 is interposed between the side posts 8 and 9, and is moveable endwise in either direction along the longitudinal axis of the rectangle defined by the plates 5 and 6. All of these posts are arranged parallel with one another.

A top cover 11 is mounted over the upper ends of the plates 5 and 6, and is spaced slightly therefrom. This cover has a depending flange 11a to limit outward movement of these plates. Four angle-shaped brackets 12 (see Figure 4) are attached to the underneath surface of the top cover by bolts 12a. Links 14 are swingably attached to these angle brackets by bolts 15. The lower ends of these links are accommodated in slots 8b and 9b fashioned in the side posts 8 and 9, respectively. Bolts 16 are used for swingably connecting the links 14 to upper portions of the side posts (see Figures 7 and 8). These links are arranged to allow the side posts to move outwardly and inwardly relative to the central post.

It will be noted from Figures 7 and 8 that two pairs of guides 17 are fastened to the central part 10 by screws 18. These guides are in the nature of flat strips, which straddle the side posts 8 and 9 and guide the latter toward and away from the central post 10. In a like manner, two pairs of guides 19 made from flat strips are anchored to the central post by screws 20. The latter guides straddle the side posts 9 and guide them toward and away from the central post.

Each side post 8 has a pair of cam tracks 21 (see Figure 5) fastened thereto by screws 21a, as clearly disclosed in Figure 7. Pins 22 are anchored to each pair of guides 17 and straddle the cam tracks 21. Accordingly, when the central post 10 is pulled upwardly in Figure 7, the guides 17, cam tracks 21 and pins 22 will move the side posts 8 and core plates 5 inwardly. When the central post 10 is pushed downwardly again, the core plates 5 will be moved outwardly. The fully expanded positions of the plates 5 are shown in Figure 9, while Figure 10 discloses the contracted positions of these same core plates.

Also, each side post 9 has a pair of cam tracks 23 anchored thereto by screws 23a (see Figure 8). Each pair of guides 19 is provided with pins 24 that straddle the cam tracks 23. Upward movement of the central post 10 in Figure 8 will cause the guides 19, cam tracks 23 and pins 24 to move the side posts 9 and core plates 6 inwardly. As the central post is moved downwardly again, the core plates will move outwardly into expanded positions.

The central post 10 extends through a non-circular opening 25 provided in the top cover 11 and projects above the latter. The upper portion of the central post has a transverse bar 26 anchored therein to facilitate moving the central post 10 upwardly and downwardly. The top cover 11 has a handle 27 secured thereto by screws 27a. This handle may be grasped by the finger tips 28 of the operator, while the latter's palm 29 extends over the top of the central post, as suggested in Figure 7. In this manner, the central post may be pushed down to expand the form.

Returning now to the construction of the hollow concrete wall B, as illustrated in Figure 1, the use of my collapsible core A during the pouring of the wall is briefly summarized as follows:

Assuming that the foundation (not shown) for the wall has been poured and the form boards 1 are supported by the retainer posts 2 and 70

spreadsers 3, a series of my collapsible cores are greased on their outer surfaces and then are supported between the form boards at the locations where the vertical air columns 4 are to be provided. The core plates 5 and 6 are moved outwardly by pushing down on the top of the central post 10. A course of concrete is poured between the form boards and around the collapsible cores.

10 This freshly poured concrete is allowed to set, which will take about four hours for an average mix. Next, the collapsible cores A are contracted by pulling the central post 10 upwardly. This will free the core plates 5 and 6 from the walls 15 of the vertical air columns 4. The cores are drawn upwardly, leaving approximately six inches of the lower end of each core in the air columns provided by the first course of concrete. The cores are expanded again, additional form 20 boards are added to those already in place, and the spreaders 3 are moved upwardly. Now a second course of concrete is poured and permitted to set. These steps are repeated until the wall has reached the desired height.

25 I claim:

1. In a collapsible core to be employed in constructing hollow concrete walls; two pairs of opposing core plates arranged to provide a form substantially rectangular in transverse cross section; each plate having bevelled marginal flanges extending lengthwise along opposing side edges thereof; the flanges on each plate overlapping and sliding on the adjacent flanges of the two adjacent plates; a side post secured to the inner surface of each plate to reinforce the latter and extending substantially throughout the length of the plate; a central post moveable endwise in either direction along the longitudinal axis of the rectangle defined by the plates; all of the 30 posts being arranged parallel with one another; and means interconnecting the central posts with all of the side posts for expanding the form outwardly while maintaining the flanges in contact when the central post is moved endwise in one direction, and for contracting the form inwardly 35 while maintaining the flanges in contact when the central post is moved endwise in the opposite direction.

2. In a collapsible core to be employed in constructing hollow concrete walls; two pairs of opposing core plates arranged to provide a form substantially rectangular in transverse cross section; each plate having bevelled marginal flanges extending lengthwise along opposing side edges thereof; the flanges on each plate overlapping and sliding on the adjacent flanges of the two adjacent plates; a side post secured to the inner surface of each plate to reinforce the latter and extending substantially throughout the length 40 of the plate; a central post moveable endwise in either direction along the longitudinal axis of the rectangle defined by the plates; all of the posts being arranged parallel with one another; means interconnecting the central posts with all of the side posts for expanding the form outwardly while maintaining the flanges in contact when the central post is moved endwise in one direction, and for contracting the form inwardly while maintaining the flanges in contact when the central post is moved endwise in the opposite direction; the plates having upper ends; a top cover mounted over the upper ends of the plates; and links swingably attached to the cover and to upper portions of the side posts; the links constituting supports from the cover for the side posts 45

and their attached plates; the links being arranged to allow the side posts to move outwardly and inwardly relative to the central post.

3. In a collapsible core to be employed in constructing hollow concrete walls; a plurality of core plates arranged to provide a conduit-like form; the plates having upper ends; a top cover mounted over the upper ends of the plates; a central post moveable endwise in either direction along the longitudinal axis of the conduit-like form; the central post extending through the cover and projecting thereabove so that the palm of a person's hand may be pressed against the top of the central post; a handle secured to the cover and positioned to have the finger tips of the person's same hand engaged thereunder whereby downward pressure of the palm will push the central post downwardly relative to the cover; and means for expanding the conduit-like form outwardly while maintaining the plates in contact when the central post is moved endwise in one direction, and for contracting the form inwardly while maintaining the plates in contact when the central post is moved endwise in the opposite direction.

4. In a collapsible core to be employed in constructing hollow concrete walls; two pairs of thin opposing core plates having flat sections arranged to provide a form substantially rectangular in transverse cross section; each plate having bevelled flanges extending the entire length thereof along opposing sides; the flanges on each plate overlapping and sliding on the adjacent flanges of the two adjacent plates; side posts removably secured to the inner surfaces of the plates to reinforce the latter and extending substantially throughout the lengths of the plates; a central post moveable endwise in either direction along the longitudinal axis of the rectangle

defined by the plate; all of the posts being arranged parallel with one another; pairs of flat plate-like guides removably fixed to the central post and straddling the side posts for guiding the latter toward and away from the central post; strip-like cam tracks removably secured to the side posts; means coacting with the cam tracks for expanding the form outwardly when the central post is moved endwise in one direction, and for contracting the plates inwardly when the central post is moved endwise in the opposite direction; the plates having upper ends; a top cover mounted over the upper ends of the plates and having a depending marginal flange to limit outward expansion of the plates; and links swingably attached to the cover and to upper portions of the side posts; the links constituting supports from the cover for the side posts and their attached plates; the links being arranged to allow the side posts to move outwardly and inwardly relative to the central post; the central post extending through the cover and projecting thereabove.
